CLAIM

The ornamental design for a toilet bowl deflector, as shown and described.

DESCRIPTION

FIG. 1 is a front elevational view of the toilet bowl deflector showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side view thereof; the broken line showing of the toilet bowl is for illustrative purposes only and forms no part of the claimed design; and,

FIG. 8 is a rear perspective view thereof.

FIG. 1

FIG. 2

FIG. 3
